UNITED STATES PATENT OFFICE.

SEYMER E. MAYABB, OF NEBRASKA CITY, NEBRASKA.

MUSIC-LEAF TURNER.

1,290,770.

Specification of Letters Patent.

Patented Jan. 7, 1919.

Application filed April 24, 1917. Serial No. 164,207.

To all whom it may concern:

Be it known that I, SEYMER E. MAYABB, a citizen of the United States, residing at Nebraska City, in the county of Otoe and

5 State of Nebraska, have invented certain new and useful Improvements in Music-Leaf Turners, of which the following is a specification.

This invention has relation to music leaf 10 turners, and more particularly to a mechanically operated device for turning the leaves of sheet music during the execution of a composition on a musical instrument.

The primary object of the invention is to 15 provide a manually operated mechanism embodying a music leaf support and associated with the piano or other musical instrument in a manner that will permit the player to turn the leaves of music with a 20 very slight pressure on an operating lever provided for the purpose, and in convenient reach of the player.

A further object of the invention is to 25 provide a device of this character having means for manually operating the same, disposed in close proximity to the keys of the piano, whereby the player may reach and press the operating finger in a minimum 30 space of time thus causing practically no interference with the proper execution of the musical composition.

The invention has for another object to 35 combine a support for the sheets of music with a suitable retaining case having operating mechanism mounted therein, so that an unsightly mechanical structure will be hidden from view; the parts being so associated as to permit them to be easily mounted upon and disengaged from the front of 40 the musical instrument.

The above and additional objects are accomplished by such means as are illustrated in the preferred embodiment and in the accompanying drawings, wherein like characters denote like or corresponding parts throughout the several views, in which;

Figure 1 is a front elevation of the device constructed in accordance with my invention.

50 Fig. 2 is a fragmentary vertical section on the line 2-2 of Fig. 1, showing the device applied to a piano.

Fig. 3 is a horizontal section on the line 3-3 of Fig. 2.

55 Fig. 4 is a fragmentary vertical section on the line 4-4 of Fig. 2.

Fig. 5 is a detail perspective view of the supporting bracket.

Fig. 6 is an enlarged detail view of one of the leaf clips.

Fig. 7 is a section on the line 7-7 of Fig. 6.

Fig. 8 is a fragmentary section on the line 8-8 of Fig. 2.

Referring to the drawing, wherein is illustrated the preferred form of my invention, and in which like numerals of reference indicate corresponding parts throughout the several views, the casing 1 is of comparatively small size and is adapted to contain the mechanism for operating the device. The casing 1 carries a shelf 2, and the shelf is joined to a back supporting panel 3, thereby forming a rack upon which the sheets of music may be arranged in the usual manner. The back of the casing is provided with loops 4 adapted to receive the fingers 5 and 6 formed on the upper and lower portions of the supporting bracket 7. This bracket is provided with a retaining flange 8 having suitable supports 9, through which screws or fastening elements may be extended for fastening the bracket to the front of the piano or other musical instrument.

Disposed in the front of the panel 3 is a pair of operating rods 10, and these are disposed substantially vertically on the face of the panel and their upper ends are journaled in a bearing 11 carried at the top edge of the panel 3. Above the bearing 11, the rods 10 are bent at right angles to provide the turning arms 12, the terminals of which carry suitable clips 13, engageable with the upper marginal edges of the sheets of music. The clips 13 are slidably mounted upon the turning arm 12 to permit the clips to slide when the pages are swung, thereby preventing tearing of the pages or leaves from the binding.

Each rod 10 projects downwardly through a suitable opening in the shelf and is rotatably mounted in a bearing 14, within the casing 1. Each rod 10 carries a rack gear, one of which is designated at 15, and the other at 16, in Fig. 3 of the drawing. Rotatably mounted in suitable bearings carried by the ends of the casing is a shaft 17, the upper end of which carries a gear wheel 18 engageable with the teeth 19 formed on a double rack bar 20. This rack bar is slidably mounted in the guide 21, the terminals of which receive the shaft 17. The double

rack bar 20 is formed by bifurcating a portion of its length and providing the teeth 19 on one outer edge and also forming teeth 22 on the inner edge of one of the legs 5 formed by the bifurcated portion. The teeth 19 are engageable with both the gear wheel 18, and the rack gear 15, while the teeth 22 are engageable with the rack gear 16.

10 In the lower end of the casing is a bracket 23 for bracing the lower end of the shaft 17, and for receiving a stud shaft 24, projecting outwardly from the front of the casing and having a crank 25 mounted 15 thereon. The inner end of the stud shaft 24 extends through the bracket 23 and carries a bevel gear 26 meshing with a bevel pinion 27 carried by the shaft 17. The end of the crank 25 is provided with an operating finger 28 upon which the player may press when he desires to actuate the operating mechanism.

It will be noted, by referring to Fig. 3 of the drawing, that a rotary movement imparted to the gear 18 will reciprocate the rack bar 20. In this figure, the mechanism is shown as in the position it will assume after one of the turning arms 12 has been swung over to turn one of the leaves of 30 music. For this reason, the rack gear 15 is shown in the position after completing the operation for turning the finger 12. The rack gear 16 has, therefore, just begun its engagement with the teeth 22, and a continued pressure on the operating finger will cause the rack bar to move farther toward 35 the right to turn the rack gear 16, thus rotating the corresponding rod 10.

From the foregoing it will be observed 40 that a very simple and durable music leaf turner has been provided, the details of which embody the preferred form. I desire

it to be understood, however, that slight changes in the minor details of construction may be made without departing from the 45 spirit of the invention or the scope of the claims hereunto appended.

I claim:

1. A music leaf turner comprising a plurality of operating rods, a gear attached to 50 each rod, a guide member supporting the gears, a rack bar formed of a bifurcated member providing parallel legs, each having one edge provided with teeth in mesh with one of the said gears, the teeth on one leg 55 terminating at a point directly opposite a point on the other leg where the teeth thereon begin so that one of the said gears will be out of mesh when the other gear is moving into mesh.

2. A music leaf turner comprising a casing, a plurality of rods extending into the casing, rack gears mounted upon the ends of the rods within the casing and disposed in the same plane, a guide member supporting the said rack gears, a double rack bar disposed in the same plane as the said rack gears and including a bifurcated portion forming a pair of legs one having teeth on 60 its inner edge and the other having teeth on its outer edge, each set of teeth being engageable with one of the said rack gears when the double rack bar is actuated, and a gear wheel engageable with the said teeth on the outer edge of one of the said legs, and 65 means for manually actuating the said gear wheel.

In testimony whereof I affix my signature in presence of two witnesses.

SEYMER E. MAYABB.
